UNITED STATES PATENT OFFICE.

CHARLES EDWARD DRAPEE, OF LEXINGTON, KENTUCKY.

HEATING APPARATUS.

Application filed December 1, 1925. Serial No. 72,531.

This invention relates to improvements in heating apparatus, for example stoves, and it consists of the constructions, combinations and arrangements herein described and claimed.

An object of the invention is to provide a hood or superheater for a stove or any other kind of circulating heater said hood being incorporated therein in such a manner as to cause the greater volume of incoming air to follow the contour of a highly heated drum, said hood having an opening or openings at the top through which the heated air is discharged at a considerable speed, thereby insuring the heating of the room in a rapid and uniform manner.

Other objects and advantages appear in the following specification, reference being had to the accompanying drawing, in which Figure 1 is a perspective view of the stove in use.

Figure 2 is a central vertical section.

Figure 3 is a detail perspective view of the hood.

In carrying out the invention provision is made of a fire pot or bowl 1 having an appropriate type of grate 2 upon which the coals are supported. The tubular drum 3 constitutes an upward extension of the fire pot, and the drum is surmounted by a semi-globular dome 4 from which the products of combustion escape by way of the pipe 5 to an appropriate flue. The fire pot 1, drum 3 and dome 4 constitute the central body or heating element of the stove which is entirely closed so far as the immediately surrounding heating space is concerned.

The fuel is introduced into the stove through a charging door 6 and ashes are removed from the pit 7 through a door 8. The shell 9 constitutes the outside jacket which is designed along such lines as to give the stove the desired appearance as illustrated in Figure 1. Here the jacket is shown to have a top 10 which is perforated both at 11 and 12 for the egress of heated air.

Brackets 13 support a tubular imperforate heat screen, or partition 14 in spaced relationship to the drum 3. Other brackets 15, secured at 16 to the dome 4 supports the hood 17 or so-called superheater in spaced relationship to the dome 4. The hood has an opening or openings 18 through which air admitted at an appropriate opening 19 in the bottom of the stove escapes

after having been forced to follow the contour of the drum 3 and dome 4 by the partition 14 and the hood 17. The latter is situated in the heating space mentioned before. The hood has a notch 20 (Fig. 3) which fits over the smoke pipe 5. The space between the hood 17 and the dome 4 is greater than the space between the partition 14 and the drum 3 for reasons which appearing in the following

Operation.

As stated before, the cool air is admitted into the heating space of the stove through an appropriate opening 19 in the bottom (Fig. 2). The partition 14 and hood 17 are intended to cause the greater volume of incoming air to follow the contour of the heating element. The partition 14 is closer to the drum 3 than it is to the shell 9, thereby making the space on the outside of the partition somewhat deeper than the space on the inside. But the volume of air passing through the inner space is intensely heated, because it represents a thinner layer and passes directly over the drum 3 which, presumably, is very hot.

It has also been stated that the space between the dome 4 and hood 17 is greater than the space between the drum 3 and partition 14. The lower edge of the hood i. e. that edge which rests upon the brackets 15 extends beyond the screen so that the space inside of the hood receives not only the extremely hot air from the internal space of the partition 14 but also some of the air from the outer space. It is now apparent that the space within the hood may be made somewhat larger as it receives double portions of air.

But the hood also follows the contour of the dome 4, and by virtue of this fact the air received thereby is subjected to the very hot dome and furthermore has imparted thereto considerable velocity which sends it directly upward through the opening 18 and out of the perforations 12. Other volumes of air, not subjected to the foregoing extreme heating action escape at the perforations 11, but the ultimate result is that all of the heated air passes upwardly in the room.

By virtue of the fact that the air is subjected to a vigorous heating action and ejected with an equally vigorous action, the

room becomes heated both quickly and uniformly. It is an obvious result that if more of the heat units of the fire can be utilized for the useful purpose of heating the air the stove in which the foregoing principle is embodied becomes more efficient than other stoves. And a further result must necessarily follow that a substantial saving in fuel will be had.

10 While the construction and arrangement of the heating apparatus is that of a generally preferred form, obviously modifications and adaptations in the form thereof herein described may be made without departing 15 from the spirit of the invention or the scope of the appended claims.

I claim:

1. Heating apparatus comprising a heating element which includes a tubular drum 20 and a substantially semi-globular dome having a lateral smoke outlet pipe, a shell constituting the outside jacket of the apparatus having air inlet and outlet openings, an open ended tubular partition in concentric 25 spaced relationship to the drum, a hood shaped substantially like the dome but being spaced farther therefrom than the partition is spaced from the drum leaving a circumferential opening for the ingress of air from 30 the space at both sides of the partition, said hood having a notch fitting over the outlet

pipe and a top central opening aligning with the shell outlet opening for the escape of heated air, and means for simultaneously supporting the partition and hood, said means including brackets carried by the drum and other brackets carried by the dome.

2. In combination with a combustion chamber having a dome at the top, supports 40 radiating therefrom, a centrally orificed hood placed upon said supports in spaced relationship to the dome providing a circumferential air inlet at the lower edge thereof for directing the air passing up the 45 side of the combustion chamber and into said inlet across the top of said dome.

3. In combination with a combustion chamber, a dome closing the top, contiguous supports radiating from both the combustion chamber and dome, the latter supports being longer than the former, a partition depending from the short supports being open at the bottom and top, and a centrally orificed hood placed upon the long supports being spaced farther from the dome than the partition is spaced from the combustion chamber thereby defining a circumferential air inlet at the lower edge thereof both inside and outside of the partition.

CHARLES EDWARD DRAPER.
